SERVO-POWER APPLICATION TO DIES
OF DIE-CASTING MACHINES

Louis H. Morin, Bronx, N. Y.

Application December 5, 1947, Serial No. 789,959

4 Claims. (Cl. 22—92)

1

This invention relates to the closure of dies in die casting machines to insure firm engagement of the dies in the operation of pressure injecting casting material into the cavity of the dies. Further, the invention deals with machines of the character described, wherein greater pressures can be used in injecting the casting material into the die cavity, thereby producing a more homogeneous and solid casting. More particularly, the invention deals with machines of the character described, having means for moving the dies into open and closed positions and a servo-power application to the dies to apply what might be termed a final squeeze or applied pressure firmly retaining the dies in closed positions under such high pressures as to withstand the pressure of injecting casting material into the die cavity.

Still more particularly, the invention comprises the use of a servo-power medium in the form of an air-actuated piston for transmitting the final squeeze pressure to the dies in retaining the same in closed position.

The novel features of the invention will be best understood from the following description, when taken together with the accompanying drawing, in which certain embodiments of the invention are disclosed and, in which, the separate parts are designated by suitable reference characters in each of the views and in which:

Fig. 1 is a diagrammatic sectional view through one die guide showing, in part, the operating mechanism with part of the construction broken away and in section; and

Fig. 2 is a view similar to Fig. 1 showing another adaptation of my invention.

In die casting machines and, particularly, machines operating at relatively high speeds, it has been a problem to securely hold the dies together or in firm abutting engagement during the operation of pressure injecting casting material into the cavity of the dies. As a result, the resulting castings have had a degree of porosity, which results in a certain amount of reject castings, which must be re-melted and formed into new castings. Methods have been employed to apply added pressure or squeeze to the dies to overcome this difficulty, but such methods have been slow in action and complicated from the standpoint of construction employed.

It is the purpose of my invention to overcome these objectionable features by providing, in combination with a die operating mechanism, a pneumatic servo-mechanism for applying to the dies the added squeeze pressure or pinch in securely retaining the dies in closed position during in-

2

jection of casting material into the die cavity, thereby decreasing porosity, if not entirely eliminating, the formation of porous or imperfect castings.

5 By employing the pneumatic-servo-power mechanism in question, a quick die action is made possible to be consistent with operating at high speed and, further, the dies may be so firmly engaged as to make it possible to utilize higher pressures in injection of casting material into the die cavity.

One advantage of the mechanism employed resides in the fact that the servo-power mechanism can be applied without interference with 15 a standard die structure, or the die supporting member of the machine. In other words, the die, including the support therefor, are not modified in any manner and standards of constructing the same can be maintained. The mechanical

20 operating mechanism is modified to the extent of providing the locking engagement of the pusher or supplemental plunger with the slide, so that the slide, in conjunction with the die, are moved in applying the final pressure to the die 25 in closing the same. The servo-power mechanism may be said to comprise an attachment and this attachment, in no way interferes with normal opening and closing of the dies and should the use of the mechanism be unnecessary in some occasions, all that will be necessary is to cut off the air supply to the piston which will maintain the pusher as a floating element, which will ratchet over the die operating slide as will be apparent.

30 35 It will also be apparent that, with the structure, employed and as later described, a minimum amount of air is required for actuating the pistons in applying the pneumatic servo-power, thus economic operation is made possible. Furthermore, the simplicity of the mechanism employed will readily adapt the same to machines of various kinds and classes, as will appear from the following detailed description of adaptations as disclosed.

40 45 In the accompanying drawing, I have shown to illustrate my invention two mechanisms for servo-power application to dies showing diagrammatically one type of die operating mechanism substantially of the type and kind disclosed in my prior patents, Numbers 2,367,303 issued January 16, 1945; and 2,379,738 issued July 3, 1945, and, still further, disclosed in my Patent Number 1,975,966 issued October 9, 1934.

To simplify the present illustration, I have 50 shown diagrammatically the means for actuati-

ing one die of each pair, it being understood that the other companion die has similar operating mechanism.

In Fig. 1 I have shown at 10, 10' adjacent abutting portions of a pair of dies, at the abutting surface 11 of which is formed a cavity 12 to form any suitable casting and, at 13, is indicated the gate, through which casting material is injected through suitable means, not shown, under pressure into the cavity 12.

The die 10 is mounted in a suitable guide 14 having an extension 15, in which the normal die operating mechanism 16 is mounted. This mechanism comprises a slide or plunger 17, which crosses over a surface of the die 10 and has an angular cam key-way 18 operatively engaging a similar type of key 19 on the die.

At 20 is shown a slide actuating member operated by any suitable means of the machine for actuating the slide 17 through a spring 21. Extending from the member 20 is a guide rod 22, which passes freely through an elongated aperture 23 in the slide 17 to compensate for movement of the slide in the servo-power application to the die, as later described. In this connection, it will also appear that a slight clearance is provided for the slide 17 in the extension 15 to also compensate for this movement.

One side surface of the slide 17 has longitudinally spaced teeth or projections 24 and arranged in the guide 14 above and at one side of the die 10 is a pusher or supplemental plunger 25 having, at its inner end, teeth or projections 26 adapted to register and ratchet with the teeth or projections 24 on the slide 17. The pusher 25 has, at its outer end, an extension 27, which opens into a cylinder or casing 28 bolted to a flanged end 29 on the guide 14, as clearly shown.

In the cylinder or casing 28 is mounted a piston 30 having a central rod 31 adapted to engage the extension 27 on the pusher 25, as clearly seen. A spring 32 is arranged between the piston and casing to normally hold the piston against the closure plate 33 of the casing or in the direction of said plate.

Centrally of the plate 33 is an air inlet passage 34 with which is coupled an air supply pipe 35, through which air under pressure forming a suitable source of supply is adapted to enter the chamber 36 of the casing or cylinder in advancing the piston 30 to apply pressure to the pusher 25 and, thus, to the die 10 through the medium of the slide 17.

In operation of the mechanism, diagrammatically shown in Fig. 1, the die 10 is moved into open and closed position through the medium of the mechanism 16 and the usual means for actuating this mechanism is not shown. Suitably timed with the operation of this mechanism when the die 10 is moved into its closed position, air will then be introduced into the cylinder 28 to actuate the piston 30, thus introducing a servo-application to the die and applying the squeeze pressure to said die, it being understood that the companion die 10' is correspondingly actuated with a duplicate mechanism, such as shown in Fig. 1. This servo-power application to the die takes place just prior to the pressure injection of casting material into the cavity 10 and immediately thereafter the pressure is released by exhaust of air from the chamber 36 and the spring 32 will free the pusher 25, thus allowing the slide 17 to timely move the die into open position in the operation of ejecting the casting. It will appear that the cylinder or casing 28 has

6 a suitable vent 37 to free air from the chamber 38 at the opposite side of the piston 30.

In Fig. 2 of the drawing, I have shown another adaptation of the invention, in which a different method of applying pressure to the dies is employed, namely through a lever which will add to or increase the applied pressure through the leverage employed. In this figure, I have shown at 10" a die, similar to the die 10, mounted 10 in a suitable guide 14' which differs from the guide 14 in dispensing with the flange 29 and in having a bracket portion 39 secured to the extension 15' thereof. In Fig. 2, the die operating mechanism 16' is the same as the mechanism shown in Fig. 1, in other words, the parts 17', 20', 21' and 22' are employed, the slide 17' having the teeth or projections, as at 24' for engagement with corresponding teeth or projections 26' on the pusher or supplemental slide 25'. The latter has an extension 27', similar to the extension 27, which projects through the open end of the guide 14', as clearly seen.

With the structure shown in Fig. 2, the guide 14' has another bracket portion 40, in which 25 is pivoted, as at 41, an operating lever 42. The lever 42 has a rounded surface 43 adapted to engage the extension 27' of the pusher 25'. The free end portion of the lever 42 extends into a recess 44 in the bracket 39 and has an offset 30 rounded portion 45 adapted to be engaged by the piston rod 31' on a piston 30'. The piston 30' is mounted in a cylinder or casing 28', substantially similar to the casing 28 and closed by a plate 33'. At 32' is shown the spring for returning 35 the piston to inoperative position, similar to the spring 32. At 34' is shown the air admission port and 35' the air pipe or tube, through which air under pressure is supplied to the chamber 36'. At 38' is shown the inner chamber of the casing, which has the vent, as at 37'.

With the structure shown in Fig. 2, the servo-power application to the die, instead of being direct as at Fig. 1, is transmitted through the lever 42. In other words, as the piston 30' is moved inwardly, the lever 42 is moved to the left and the rounded extension 43 applies pressure to the extension 27' of the slide 25' in applying the squeeze pressure to the die 10".

It will be understood that a similar mechanism to the mechanism shown in Fig. 2 will be employed in connection with the companion die, as in the illustration in Fig. 1 of the drawing.

It will be apparent that, in the accompanying drawings, the servo-power application to dies has been applied to one type and kind of die operating mechanism. It will be apparent, also, that the same applied pressures can be employed in conjunction with machines having different types and kinds of die operating mechanism or to dies of casting machines of any type or kind, particularly where it is desirable to firmly maintain dies in closed position with each other in order to withstand high pressures that prevail in injecting casting material into the dies.

Having fully described my invention, what I claim as new and desire to secure by Letters Patent is:

1. In a die casting machine of the type wherein a pair of dies are movably supported in opposed relation to each other and are periodically moved into and out of closed position and a casting material is injected under pressure into a casting cavity defined by the opposing faces of the dies when they are in closed position, the combination of a die-actuating member engaging with

each of the dies for moving the dies into and out of closed position, said die-actuating members being movable transversely of the dies, a pair of movable pusher members supported in opposing relation to each other, each of said pusher members being located on the side of one of the die-actuating members remote from the dies with its center line in a vertical plane perpendicular to the parting line of the dies at the mid point of the dies and pressure means for moving each of said pusher members into engagement under pressure with the side of the respective die-actuating members remote from the dies when the dies are in closed position, said pressure means exerting pressure on the dies through the pusher members and the die-actuating members to maintain the opposing faces of the dies in contact during the injection of casting material into the die cavity.

2. In a die casting machine of the type wherein a pair of dies are movably supported in opposed relation to each other and are periodically moved into and out of closed position and a casting material is injected under pressure into a casting cavity defined by the opposing faces of the dies when they are in closed position, the combination of a die-actuating member engaging with each of the dies for moving the dies into and out of closed position, said die-actuating members being movable transversely of the dies and having a serrated surface extending along the side thereof remote from the die, a pair of movable pusher members supported in opposing relation to each other, each of said pusher members being located on the side of one of the die-actuating members remote from the dies with its center line in a vertical plane perpendicular to the parting line of the dies at the mid point of the dies and pressure means for moving each of said pusher members into engagement under pressure with the side of the respective die-actuating members remote from the dies when the dies are in closed position, said pressure means exerting pressure on the dies through the pusher members and the die-actuating members to maintain the opposing faces of the dies in contact during the injection of casting material into the die cavity.

3. In a die casting machine of the type wherein a pair of dies are movably supported in opposed relation to each other and are periodically moved into and out of closed position and a casting material is injected under pressure into a casting cavity defined by the opposing faces of the dies when they are in closed position, the combination of a die-actuating member engaging with each of the dies for moving the dies into and out of closed position, said die-actuating members being movable transversely of the dies, a pair of movable pusher members supported in opposing relation to each other, each of said pusher members being located on the side of one of the die-actuating members remote from the dies with its center line in a vertical plane

perpendicular to the parting line of the dies at the mid point of the dies and pressure means for moving each of said pusher members into engagement under pressure with the side of the respective die-actuating members remote from the dies when the dies are in closed position, each of said pressure means including an air cylinder and a piston in said cylinder operatively engaging with one of the pusher members, said pistons moving the respective pusher members in the direction of the closing movement of the die associated therewith and into engagement with the sides of the die-actuating members remote from the dies upon admission of air pressure to the respective cylinders.

4. In a die casting machine of the type wherein a pair of dies are movably supported in opposed relation to each other and are periodically moved into and out of closed position and a casting material is injected under pressure into a casting cavity defined by the opposing faces of the dies when they are in closed position, the combination of a die-actuating member engaging with each of the dies for moving the dies into and out of closed position, said die-actuating members being movable transversely of the dies, a pair of movable pusher members supported in opposing relation to each other, each of said pusher members being located on the side of one of the die-actuating members remote from the dies with its center line in a vertical plane perpendicular to the parting line of the dies at the mid point of the dies and pressure means for moving each of said pusher members into engagement under pressure with the side of the respective die-actuating members remote from the dies when the dies are in closed position, each of said pressure means including an air cylinder, a piston in said cylinder and a power-increasing lever connecting said piston to one of the pusher members, said levers moving the respective pusher members in the direction of closing movement of the die associated therewith and into engagement with the sides of the die-actuating members remote from the dies upon admission of air under pressure to the respective cylinders.
